BELT BUCKLE

Harold N. Trout and Fielding S. Ellis, Norristown, Pa., assignors of one-third to Harold B. Slemmer, Lederach, Pa.

Application July 30, 1932. Serial No. 626,310

5 Claims. (Cl. 24—191)

This invention relates to belt buckles, and has for an object to provide an improved type of buckle wherein the loose end of the belt is positioned beneath the section connected with the buckle.

A further object of the invention is to provide an improved type of belt buckle wherein the belt is not inserted through any loops or other restraining parts, but is retained only under a hinged keeper.

A further object of the invention is to provide a belt buckle having a body part to which one end of the belt is permanently attached, and with a keeper hinged to one side of the buckle and adapted to swing clear of the buckle to permit the loose end of the belt to be inserted laterally or otherwise along the back of the body of the buckle to be enclosed by the keeper when the keeper is closed.

20 A further object of the invention is to provide an improved type of keeper for use with the buckle body.

The invention therefore comprises a buckle body having means for permanently attaching one end of a belt with a keeper hinged to the back of the buckle and to close into engagement with the loose end of the belt and with an abutment against which the keeper engages to relieve strain.

30 The drawing illustrates an embodiment of the invention and the views therein are as follows:

Figure 1 is a view of the buckle in front elevation with sections of a belt connected therewith.

35 Figure 2 is a view of the reverse side of the buckle with the ends of the belt associated therewith.

Figure 3 is an edge view of the buckle as indicated by arrow 3 at Figure 2.

40 Figure 4 is a sectional view through the buckle and belt as indicated by line 4—4 at Figure 2.

Figure 5 is a transverse section through the buckle and belt as indicated by line 5—5 at Figure 3, and

45 Figure 6 is an inverted perspective view of the keeper.

Like characters of reference indicate corresponding parts throughout the several views.

The improved belt buckle, which forms the subject matter of this application, comprises a body section 10 preferably curved to correspond approximately to the curvature of the body, and with upper and lower flanges 11 and 12.

50 The body is provided with a bar 13 which extends transversely across the body and retains one end as the end 14 of the belt permanently

in connection therewith. No particular novelty is claimed in the present application in regard to this bar and any approved means for attaching this end of the belt is within the scope of the invention.

One of the flanges as the flange 12, which is preferably the lower flange, is provided with eyes 15 forming a part of a hinge, the other part being the eye 16 carried by the keeper 17, a pintle 18 forming a hinge.

The keeper 17 is in the form of a bar which extends entirely transversely across the body and is provided with an inturned end 19 which, when closed, fits under the upper flange 11.

55 This keeper 17 is provided along one edge with a row of teeth 20 which when the keeper is closed, engages the section 21 of the belt.

To maintain the keeper in closed position, any approved type of fastening member may be employed. Specifically, the inturned end 19 is provided with an indentation 22, and a like indentation 23 is formed in the flange 11. The keeper 17, being constructed of resilient material such as sheet metal, permits the end 19 to snap under the flange 11 until the indentations 22 and 23 coincide which holds the keeper 17 in closed position.

60 As the strain of the belt is in the direction indicated by the arrow at Figure 2, an abutment 24 is formed as an extension of the flange 11 and against which the keeper 17 engages when in closed position, and which takes the strain of the tension exerted upon the belt.

In operation, the belt is placed about the body and the keeper 17 swung to open position. The

70 completely open position is indicated in dotted lines at 17' in Figure 5. Such completely open position is not necessary but is illustrative. The belt end 21 is then slipped beneath the keeper

either longitudinally or laterally as found most convenient. The belt is tightened to the necessary tension and the keeper 17 closed. As the

75 loose end of the belt 21 is engaged between the section 14 and the body, the pressure of the body

on this loose end assists the buckle in maintaining the proper adjustment. It is obvious, of course, that when the belt is to be tightened or

80 loosened, the keeper is simply opened sufficiently to disengage the teeth 20 from engagement with the belt, the belt removed to the position required, and the keeper again closed.

85 Of course, the belt buckle herein illustrated may be modified and changed in various ways without departing from the invention herein set

90 forth and hereinafter claimed.

The invention is hereby claimed as follows:

1. A belt buckle comprising a body having means for attaching a belt end thereto, flanges along the sides of the body perpendicular to said retaining means, a keeper hinged to one of the flanges, means carried by the keeper for latching engagement with the other flange, penetrating points carried by the keeper adapted to engage the other belt end, and an abutment carried by the body against which the keeper is positioned when closed.

2. A belt buckle comprising a body, means to fix one belt end against the rear face of the body, and means hinged to one side of and swinging transversely across the body and belt to clamp said belt end, and the other belt end in superposed contact between said clamping means and the body, in such manner that stress applied to the belt tends to move the superposed ends in opposite directions.

3. A belt buckle comprising a curvilinear body having means for retaining a belt end against the concave rear face thereof, flanges along the sides of the body perpendicular to said retaining means, a keeper hinged to one of the flanges, means carried by the keeper for latching engagement with

the other flange, penetrating points carried by the keeper adapted to engage the other belt end and force it within the concavity, and an abutment carried by the body against which the keeper is positioned when closed.

4. A belt buckle comprising a body, means to fix one belt end against the rear face of the body, and means swinging transversely of the body and belt to clamp said belt end, and the other belt end in superposed contact between said clamping means and the body, in such manner that the stress exerted upon said belt in use tends to move said superposed ends in opposite directions.

5. A belt buckle comprising a curvilinear body, means to fix one belt end against the concave rear face of the body, and keeper means hinged to one curvilinear side of the buckle body to swing transversely thereof and of said belt end and the other belt end to clamp said belt ends in superposed contact between said clamping means and the body and bow the superposed sections into the concavity.
